GUN PERFORATOR

Jacques Honoré Castel, Houston, Tex., assignor
to Perforating Guns Atlas Corporation, Houston, Tex., a corporation of Delaware

Application August 12, 1948, Serial No. 43,917

5 Claims. (Cl. 164—0.5)

1

This invention relates to a gun perforator.

The invention has been designed primarily to be used to shoot bullets through the casing of a well for the purpose of bringing the inside of the casing into communication with the porous earth formation around it from which it is desired to produce a fluid.

Frequently at the time the casing is perforated with the gun the well is filled with fluid, such as water, mud, oil and the like. In a deep well the hydrostatic pressure developed by this fluid becomes very great, attaining, currently, ten thousand pounds per square inch. It is the object of this invention to provide a gun perforator which is simple in construction and which will prevent the fluid of the well from entering the gun perforator, and specifically, the powder chamber where it would wet the powder and cause the gun to misfire.

It is another object of the invention to provide a novel type of bullet holder that will maintain the bullet in the desired position with respect to the barrel and the powder chamber irrespective of the hydrostatic pressure created by the fluid outside of the gun.

It is still another object of the invention to increase the penetration power of the bullet, for a given length of barrel, by holding the rear part of the bullet inside of the powder chamber, thus artificially lengthening the travel of the bullet while the propelling power of the gases is applied behind it.

It is a further object of the invention to increase the penetration power of the bullet by providing, between the powder chamber and the gun bore, a section of progressively decreasing diameter which guides progressively the gases from the powder chamber to the much smaller diameter bore thus avoiding any turbulence of the gases and loss of power.

It is a further object of the invention to provide a combination of bullet and bullet holder that will resist a very high hydrostatic pressure of the well, which at the same time will not offer any undue resistance to the motion of the bullet when the ignition of the powder begins, thus eliminating the possibility of the powder detonating and, as a consequence, damaging or destroying the gun.

A still further object of the invention is to provide a gun perforator in which the ignition of the main powder load is caused by a powerful auxiliary ignition charge, or booster, with the result that the main charge is ignited more quickly and more uniformly than by the regular fuse embedded in powder.

2

Other objects and advantages will be apparent from the following specification which is illustrated by the accompanying drawings wherein:

Figure 1 is a side elevation of a preferred form of gun perforator.

Figure 2 is a cross-sectional view taken on the line 2—2 of Figure 1.

Figure 3 is a side elevation of a bullet employed.

Figure 4 is a cross-sectional view of a bullet holder, and

Figure 5 is a side elevational view of the bullet and holder assembled, the holder being shown in section.

Referring now more particularly to the drawings wherein like numerals of reference designate the same parts in each of the figures, the numeral 1 designates the main body of the gun perforator whose upper end is screw threaded into the adjacent end of a bell housing 2. There is a cable

20 3 which has its metallic armor clamped in the rope socket 4 to support the gun and said cable has an inner insulated core 5 to lead the electric current to the various ignition chambers. This core 5 extends through the channel 6 in the body 1 and it then follows the groove 7, cut in the periphery of the gun body, to connect in parallel all the resistance plugs in the body, such as 8. The resistance plugs carry resistances 9 which are in series with the leads 10 that carry the current to the ignition plugs 11. Generally the resistance value of resistances 9 changes from plug to plug or from series of plugs, according to the sequence of firing desired.

The gun body carries a number of gun chambers, each one having one powder chamber 12, a threaded igniter socket 12a, one barrel 13, one bullet holder 14, one seal ordinarily made of a resilient compound 15, one gasket 16, and a load of powder 17. In the igniter socket 12a, shown in more detail in Figure 2, is the screw-threaded igniter body 18.

The igniter body, made of heat treated steel, carries a center bore into which is inserted the firing pin 19, insulated by a tough insulation material 20. A short fuse 21 is soldered one end 45 to the firing pin 19, and the other end to the mass of the igniter body. There is a cup 22 which is filled with loose powder and is inserted at the inner end of the igniter. There is a washer 23 under the igniter flange and a washer 24 under the nut 25 which keep the fluid of the well from entering the gun. The leads 10 are connected to the resistance plugs 8.

Referring to Figure 2, the powder chamber 12 carries a counterbore 26 on the side adjacent the cartridge and into which seats rather loosely the

bullet holder 14. The bullet holder rests on the shoulder 27 around the powder chamber and keeps both the bullet and the bullet holder in position in the chamber, no matter how great is the pressure applied by the well fluid on the seal 15.

The bullet shown in Figure 3 is made of specially heat treated alloy steel and carries a tapered groove 28, the taper being toward the point of the bullet.

The bullet holder is generally made of mild steel. Its diameter is only a few thousandths of an inch smaller than the counterbore 26 of the powder chamber. The shape of the inner surface of the counterbore 26 is such that it allows ample strength to the bullet assembly and at the same time leads progressively the gases from the burning powder in the chamber to the much smaller diameter of the barrel bore, thus reducing to a minimum the losses of power through turbulence of the gases. The top of the holder which comes into contact with the barrel 13 is preferably tapered not only to keep the explosion gases from leaking between itself and the barrel, but mainly to make the holder resistant to much higher pressures than would a flat holder of the same thickness.

To assemble the bullet and the bullet holder the point of the bullet is forced through the holder until the tapered groove 28 receives the rim 29 of the holder. Since the bore through rim 29 is smaller than the diameter of the bullet, the bullet is held in the holder.

With this type of bullet assembly, the greater the hydrostatic pressure on seal 15, the higher the pressure of the bullet on the rim 29 of the holder 14. But as this pressure on the rim 29 increases, the grip on the bullet increases at the same time. The bullet cannot enlarge the bore through rim 29 because the latter is held in the counterbore and cannot expand. Tests have repeatedly shown that bullet holders having a rim thickness of no more than $\frac{1}{16}$ to $\frac{1}{8}$ and a tapered groove of no more than .015" deep, hold pressure in excess of 35,000 pounds per square inch, which is very ample for the actual conditions encountered in the wells to be perforated. It is absolutely indispensable, from a safety point of view, that the bullet and its holder stand very great pressures. If one holder were to fail under the pressure of the well, the bullet would be projected at great speed toward the chamber and would ignite the powder by the impact developed. This would result in one bullet perforating the casing at the wrong place, necessitating very expensive repair work to the well, and possibly even the loss of the well.

It seems simple at first sight to make the bullet holder hold higher pressure by just increasing the thickness of the metal. But this will have several objections. First, it will increase the price of the holder. Second, it will take up that much more space of the powder chamber, with the consequence of a loss of power. Third, and more important, it will make it much more difficult for the bullet to leave the holder when the powder is fired. As a consequence, the pressure will have to become very great inside of the chamber before the bullet will start moving and such pressure may become high enough to cause the powder to detonate instead of burning normally, and cause the explosion of the gun.

The type of bullet holder described holds very high pressure from the outside, but on the contrary, when the pressure is from inside the cham-

ber, such as happens when the gun is fired, the bullet will leave its holder very easily, on account of the smallness of the taper of the groove 28. This means that the pressure at the inside of the chamber will not become excessive before the bullet starts moving inside the barrel bore, thus eliminating the possibility of damage to the gun, as mentioned above.

Loading the gun preparatory to the gun perforation consists in inserting one igniter in each one of the igniter sockets 12a, one powder load 17 in chamber 12, one bullet holder assembly 14 in each counterbore 26, one gasket 16, and one seal 15 in each barrel 13 and screwing every barrel in the corresponding threaded socket in the gun body. The gun is then ready to be lowered into the well to the desired depth by means of the cable 3 which is spooled on a cable drum at the surface. When this depth is reached, a current is sent through the conductor 5 of the cable. This current goes to the various igniters 18 with an intensity apportioned to the value of the resistances 9. When the current in one igniter is high enough to make the fuse 21 red hot, the powder in cup 22 is ignited, which in turn ignites suddenly the main powder charge 17 which then drives the bullet with a high muzzle velocity.

When all the chambers have been fired, the gun is brought to the surface to be reloaded and used again.

What I claim is:

1. In a gun perforator, a gun body having a powder chamber therein, a barrel in the body having a bore in communication with the powder chamber, a bullet fitted into the inner end of the bore, said bullet having an external, annular, groove which tapers toward the point of the bullet and a perpendicular shoulder in said bullet groove to prevent backward movement, an annular bullet holder clamped between the barrel and body and having an outwardly converging rim which interlocks in said groove.

2. In a gun perforator, a gun body having a powder chamber therein, a barrel in the body having a lengthwise bore of smaller transverse diameter than the powder chamber and whose inner end is adjacent said chamber, an annular bullet holder removably clamped between the barrel and the body, the inner side of the bullet holder forming a wall of the main powder chamber and which is of a progressively decreasing diameter towards the barrel.

3. In a gun perforator, a body having a main powder chamber therein and an ignition charge chamber in communication with the main powder chamber, a barrel in the body having a bore of smaller transverse diameter than the main powder chamber and whose inner end is adjacent said main powder chamber, a bullet fitted into the inner end of the bore and having an external annular groove, an annular bullet holder clamped between the barrel and the body and having an outwardly converging rim which interlocks with said groove, the innerside of said bullet holder forming a wall of the main powder chamber and which is of a progressively decreasing diameter toward the barrel.

4. In a gun perforator, a body having a main powder chamber therein, a barrel in the body having a bore of smaller transverse diameter than the main powder chamber and whose inner end is adjacent said main powder chamber, a bullet fitted into the end of the bore and having an external annular groove tapering toward the point of the bullet and a perpendicular shoulder

in said bullet groove to prevent backward movement, an annular bullet holder clamped between the barrel and the body and having an outwardly converging rim which interlocks with said groove, said bullet holder having a wall coextensive with the wall of said chamber and of progressively decreasing diameter toward said barrel.

5. In a gun perforator, a body having a powder chamber therein, a barrel in the body having a bore of smaller diameter than the chamber and whose inner end is adjacent said chamber, said body having a counterbore about said chamber adjacent said barrel, a bullet fitted into the end of the bore and having an external annular groove tapering toward the point of the bullet and a perpendicular shoulder in said bullet groove to prevent backward movement, an annular bullet holder in said counterbore clamped between the barrel and the body and having an outwardly

converging rim which interlocks with said groove, said bullet holder having a tapered outer face in engagement with said barrel and an inner surface coextensive with the wall of said chamber, said inner face being of progressively decreasing diameter toward said barrel.
